UNITED STATES PATENT OFFICE.

EMIL BENTE AND PAUL STUHLMANN, OF BARMEN, GERMANY, ASSIGNORS TO MAX HENKELS, OF NEW YORK, N. Y.

LACE.

Application filed December 27, 1922. Serial No. 609,271.

To all whom it may concern:

Be it known that we, EMIL BENTE and PAUL STUHLMANN, citizens of the German Empire, residing at Barmen, Germany, have invented certain new and useful Improvements in Lace, of which the following is a specification.

Our invention relates to machine-braided lace of the type in which any desired patterns are formed by filling parts of the lace-net by arranging a group of threads in the longitudinal direction of the lace and leading another group of threads to and fro in the transverse direction between the longitudinal threads, said transverse threads interlacing said longitudinal threads in a weave-like manner, and at the same crossing each other at intervals. In the known lace of this kind the crossing points of those threads which run to and fro in the transverse direction of the fabric and which may be termed the filling threads are arranged exactly in the middle between each two longitudinal threads so that when looking at the lace in its longitudinal direction, there is in the space between each two adjacent longitudinal threads one crossing of threads always immediately followed by another. In consequence thereof the patterns, especially such of great extent, make a hard and monotonous impression. Furthermore the production of so-called covering or body-bearing patterns requires not only a large quantity of thread-material, but also much time.

In our new lace the patterns are also formed by filling parts of the lace-net by arranging a group of threads in the longitudinal direction of the lace and leading another group of threads to and fro in the transverse direction between said longitudinal threads, the filling threads thereby interlacing the longitudinal threads and crossing each other at intervals. In contradistinction to the known lace, however, the mutual crossings of the filling threads are laterally displaced with respect to each other and to the longitudinal threads so that the filling threads at certain places pass the spaces between each two longitudinal threads without crossing one another, whereas at some places they cross each other between each two longitudinal threads once or even several times. In consequence of

the displacement of their mutual crossings 55 the filling threads, at certain places, run almost at right angles to the longitudinal threads and parallel to one another, while at certain other places, i. e. at the crossing points, they take a diagonal course, and a 60 more diagonal course than in the known lace. Thus not only the impression of hardness and monotonousness is avoided, but, on the contrary, a very pleasant filling even of large parts of the lace-net is obtained. 65 Furthermore the production of patterns, and also of covering patterns, by filling parts of the lace-net is a more rapid one, while at the same time the quantity of thread-material required for producing any 70 desired pattern is smaller than in the known lace.

Our new lace is shown, by way of example, on the annexed drawing, in which—

Fig. 1 represents a piece of lace in natural size,

Fig. 2 is a part of that lace drawn on a greatly enlarged scale, and

Fig. 3 is a part of the known lace of the kind referred to, drawn on the same scale 80 as Fig. 2.

Referring first to Fig. 1 the lace shown comprises a net-like ground-work A with irregularly shaped meshes. To this lace a pattern B having substantially the form 85 of an octagonal ring is applied by filling certain parts of the lace-net in the following manner.

As illustrated in Fig. 2 a group of some- 90 what heavily tensioned braiding-threads a^1, a^2, a^3, a^4 is conducted straight through in the longitudinal direction of the fabric, while a second group of slightly tensioned threads b^1, b^2, b^3, b^4 is led to and fro in the transverse direction of the lace between 95 said longitudinal threads a^1, a^2, a^3, a^4 . The transverse threads (hereafter termed the filling threads) interlace with the longitudinal threads in a weave-like manner, furthermore they cross each other at intervals.

As far as above described the formation 100 of the pattern is the same as in the known lace shown in Fig. 3. But there is a great difference in the arrangement of the crossing points of the filling threads. In the known lace (see Fig. 3) the filling threads b^1, b^2, b^3, b^4 cross each other in the middle between each two adjacent longitudinal threads $a^1, a^2, a^3,$

a^4 so that the crossings x, x between the threads a^1, a^2 as well as the crossings y, y between the longitudinal threads a^2, a^3 and finally also the crossings z, z between the threads a^3, a^4 lie (looked at in the longitudinal direction of the fabric), one immediately behind the other. From this a certain hardness and monotonousness of the filling results; besides, there are between the crossings, y, y comparatively large spaces which make a bad impression.

According to our invention the filling threads b^1, b^2, b^3, b^4 running to and fro between the longitudinal threads a^1, a^2, a^3, a^4 are led in such a manner that the mutual crossings of said threads are laterally or transversally displaced with respect to one another and to the longitudinal threads b^1, b^2, b^3, b^4 . In the example shown in Fig. 2, certain of those crossings x, x which in the known lace lie between the longitudinal threads a^1, a^2 , for instance, every third of said crossings (marked x^1 in Fig. 2), is placed not in the space between the threads a^1, a^2 , but in the space between the threads a^2, a^3 , while at the same time every third of the crossings y (marked y^1) is arranged in the space between the threads a^3, a^4 instead of between the threads a^2, a^3 . Finally, every third crossing z (marked z^1) is taken from the space between the longitudinal threads a^3, a^4 and placed on the outside of the thread a^4 . By these means the course of the filling threads within the filled part of the lace-net, although regular, appears to be an irregular one. The threads a^1, a^2, a^3, a^4 , at certain places, run parallel with each other in the transverse direction of the fabric, while, at other spots, they run diagonally, thereby crossing each other once or several times. Thus a vivid filling even of extended parts of the lace-net is obtained. At the same

time the inconveniently large spaces between the crossings y, y are avoided.

Of course the crossings of the filling threads may be displaced at pleasure to the one or the other side of the longitudinal threads. Whereas in the upper and in the middle filled part of Fig. 2 the crossings y^1, x^1 and z^1 are moved downwardly, they are in the lower filled part of the same figure displaced upwardly. If desired certain crossings may also be transferred alternately to one or the other side. Furthermore instead of displacing every third of the crossings x, y and z , respectively, there may also another rule be followed. Therefore, we wish to state that our invention is not limited to the exact lace illustrated on the drawing; on the contrary many alterations and variations may suggest themselves to those skilled in the art without departing from the scope of our invention as pointed out in the claim.

Claim:

Machine braided lace presenting the appearance of hand made lace, which comprises warp pillars of tightly tensioned threads interbraided with light tensioned threads, and filled-in spaces between said warp pillars, comprising transverse interlaced threads of two adjacent warp pillars, the interlaced threads having irregular crossings in said spaces, some of these crossings being interlocked with the remaining pillars threads, and the remainder of the crossings being irregularly disposed between the pillars.

In testimony whereof we affix our signatures in presence of two witnesses.

EMIL BENTE.

PAUL STUHLMANN.
